UNITED STATES PATENT OFFICE.

HENRY HAASE, OF PHILADELPHIA, PENNSYLVANIA, ASSIGNOR TO THE
HENSEL, COLLADAY COMPANY, OF PENNSYLVANIA.

DESIGN FOR A SKIRT-PROTECTOR.

SPECIFICATION forming part of Design No. 29,652, dated November 8, 1898.

Application filed October 12, 1898. Serial No. 693,348. Term of patent 14 years.

To all whom it may concern:

Be it known that I, HENRY HAASE, a citizen of the United States, residing in the city and county of Philadelphia, State of Pennsylvania, have invented and produced a new and original Design for a Skirt-Protector, of which the following is a specification, reference being had to the accompanying drawings, forming part thereof.

10 The leading feature of my design for a skirt-protector is a head, a brush pendent therefrom, and a facing on said head, consisting of striped bars alternately wide and narrow.

Figure 1 represents a side elevation of a 15 skirt-protector embodying my design. Fig. 2 represents a section thereof on line $x x$, Fig. 1.

In the drawings, A designates a piece of skirt-protector embodying my design, the same consisting of the head B, the brush C, and the striped bars D on said head, the same being alternately wide and narrow. On the upper edge of the head are the loops E, and on the edge thereof adjacent to the brush is the broken row of stripes F. 25

Having thus described my invention, what I claim as new, and desire to secure by Letters Patent, is—

The design for a skirt-protector substantially as shown and described.

HENRY HAASE.
